J. C. HENDRICKSON

TYPEWRITER PLATEN

Filed July 19, 1923

Inventor
J. C. Hendrickson

Attorney
John Salter Jr.

UNITED STATES PATENT OFFICE.

JOHN C. HENDRICKSON, OF BROOKLYN, NEW YORK.

TYPEWRITER PLATEN.

Application filed July 19, 1923. Serial No. 652,595.

To all whom it may concern:

Be it known that I, JOHN C. HENDRICKSON, a citizen of the United States, residing at Brooklyn, in the county of Kings and State of New York, have invented certain new and useful Improvements in Typewriter Platens; and I do hereby declare the following to be a full, clear, and exact description of the invention, such as will enable others skilled in the art to which it appertains to make and use the same.

The principal object of the present invention is the provision of a platen for typewriting machines which will insure clear impressions, reduce the noise incident to the impact of the type therewith to the smallest amount possible to cushion the blow resulting from the type striking the platen, to materially reduce the weight and finally to produce a resilient platen which absorbs shock and enables the operator to increase speed.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a front view of a typewriter platen embodying the invention, parts being broken away,

Figure 2 is a transverse section on the line 2-2 of Figure 1,

Figure 3 is a transverse section on the line 3-3 of Figure 1, and

Figure 4 is a perspective view of the skeleton core.

Corresponding and like parts are referred to in the following description and designated in the several views of the drawings by like reference characters.

The platen comprises a skeleton core and a plurality of enveloping layers of different materials which combine to produce a platen which is both light, resilient and noise-deadening. The skeleton core comprises a plurality of bars 1 grouped about an axis and connected by ends 2 and an intermediate strut 3, the several parts being preferably of integral formation. The core, while preferably cast of aluminum, may consist of any ma-

terial and constructed in any preferred way. It is observed that the platen may be adapted to any make of machine by fitting suitable ends to the core, said ends being attachable in any preferred way. Spurs 4 project outwardly from the bars 1 and provide elements for securing the body of the platen to the core.

A core sleeve 5 is slipped upon the skeleton core and the spurs 4 become embedded therein and assist materially in holding the sleeve in the required adjusted position. The sleeve 5 functions as a cushion, is light and tends to absorb type bar noise and to lessen the jar incident to the impact of the type bar with the platen. While it is preferred to employ a cork sleeve 5, it is to be understood that said sleeve may be of any light resilient material.

A sleeve 6, preferably of soft rubber, is stretched over the cushioning sleeve 5 and further assists in deadening the noise resulting from the type striking the platen. The sleeve 6 may consist of felt or other noise reducing material.

A metal sleeve 7 of aluminum or zinc envelops the sleeve 6 and provides a solid foundation for the outer sleeve or covering to insure clear impressions and also maintain the outer sleeve or cover in proper shape, and furthermore enables the outer cover or sleeve to be readily replaced when worn. A sleeve or cover 8 is fitted upon the metal sleeve 7 and may be held in place by a suitable adhesive and being backed by the metal sleeve maintains its shape and insures a clear impression and moreover may be readily replaced when worn at a comparatively small cost.

What is claimed is:

1. A platen having a skeleton core provided with ends, spaced longitudinal bars extending from one of said ends to the other of said ends, a strut for said bars intermediate said ends marginally terminating inwardly of the outer surfaces of the bars, and a cushioned covering on the core.

2. A platen having a core, a sleeve surrounding the same of substantially rigid material, said sleeve being interiorly and exteriorly lined with rubber, and a resilient sleeve interposed between the core and inner lining of rubber to serve as a cushion.

3. A platen having a skeleton core provided with ends, spaced substantially longitudinal bars extending from one of said ends

to the other of said ends, a strut for said bars intermediate said ends and spurs integral with the core, and a cushioned covering on the core penetrated by and retained in place 5 by said spurs.

4. A platen having a skeleton core provided with ends, spaced substantially longitudinal bars extending from one of said ends to the other of said ends and integral thereto, a strut integral with said bars intermediate said ends marginally terminating inwardly of the outer surfaces of said bars, spurs integral with said bars, and a cushioned covering on the core penetrated and held in 10 place by said spurs.
5. A core for a platen or the like having

ends, substantially longitudinal bars extending from one of said ends to the other of said ends and being spaced apart and integral with said ends, a strut integral with said bars disposed intermediate said ends and marginally terminating inwardly of the outer surfaces of the bars, and cushion-securing spurs integral with the bars and extending outwardly therefrom. 20

25 In testimony whereof I affix my signature in presence of two witnesses.

JOHN C. HENDRICKSON.
